UNITED STATES PATENT OFFICE.

WILLIAM WISHINSKY, OF NEW YORK, N. Y.

WATCHCASE.

Application filed July 9, 1927. Serial No. 204,552.

This invention relates to watch cases and refers more particularly to a combined watch case and fountain pen cap in which the watch case constitutes a closure for one end of the 5 cap.

One of the principal objects of the present invention is to provide as a new article of manufacture, a novelty fountain pen cap, a portion of which serves as a watch case for 10 housing a watch movement.

The invention furthermore comprehends the combination of a watch case and fountain pen cap in which the watch case includes mating sections adapted to be associated with the 15 pen cap section to constitute a closure for the cap while the pen cap portion operates to lock the watch case sections in associated relation.

Other objects reside in the simplicity of 20 construction, the economy with which the same may be produced, and the general utility derived from the combination.

With the above recited and other objects in view, reference is had to the following description and accompanying drawings in 25 which there is exhibited one example or embodiment of the invention, while the appended claims define the actual scope of the invention.

30 In the drawing—

Figure 1 is a face view of a fountain pen equipped with a combined cap and watch case constructed in accordance with the invention;

35 Fig. 2 is a side view thereof;

Fig. 3 is an enlarged longitudinal sectional view through the combined pen cap and watch case;

Fig. 4 is a transverse sectional view taken 40 approximately on the line 4—4 of Fig. 3;

Fig. 5 is a collective perspective view of the watch case sections in juxtaposition.

Referring to the drawings by characters of reference, 10 designates a tubular fountain 45 pen cap, and 11 and 12 a pair of mating substantially semi-tubular watch case sections. The section 11 is provided with reduced opposite ends 13 and 14 and the section 12 with reduced opposite ends 15 and 16. When the 50 sections 11 and 12 are mated or in associated relation, the reduced ends 13 and 15 thereof are adapted to fit or interengage within the outer end of the fountain pen cap 10. The interengagement of the reduced ends 13 and 55 15 is preferably established by a threaded connection which consists of an internal

thread 17 at the outer end of the cap 10 and an external thread 18 on the mated reduced ends 13 and 15 of the watch case sections. It thus follows that the watch case sections serve 60 as a closure for the outer end of the fountain pen cap, while said fountain pen cap functions in the capacity of a lock to hold the watch case sections in mated or assembled relation. The outer reduced ends 14 and 16 65 are designed to receive therethrough a ring or annulus 19 for locking the outer ends of the watch case sections against separation. Preferably the outer reduced ends 14 and 16 when mated are provided with an exterior 70 thread 20, while the ring or annulus is formed with an internal thread 21. If desired, the ring or annulus 19 may serve as a means for associating the retaining ring 22 with the structure. The watch case section 12 is 75 formed on its inner flattened face 23 with a transverse cutaway portion or groove 24, which extends axially from the point spaced from the opposite reduced ends 15 and 16, while the inner flattened face 25 of the section 80 11 is provided with longitudinally extending parallel flanges 26 of a length to snugly fit within the cutaway portion 24, so that the sections when mated define a space or compartment for receiving and housing the 85 movement 27. In order to provide additional means for securing the movement 27 within the section 11 prior to the assembly of the section 12 therewith, the flanges at the point adjacent the flat inner face 25 are formed with internal longitudinal grooves 28 while the movement is provided with longitudinal tongues 29 adapted to interfit with the grooves. This necessitates the sliding of the movement 27 longitudinally or axially to the 95 position between the flanges 26. After the movement 27 is arranged between the flanges 26, the stem 30 of the movement is inserted through an opening 31 in one of the flanges 26. The section 12 is then mated with the 100 section 11 and the reduced ends 13 and 15 of the mated sections 11 and 12 are interengaged with the fountain pen cap 10, the ring or annulus 19 is applied, and the movement is then enclosed or housed and forms part of the 105 fountain pen cap. The section 11 is further provided with an opening 32 for exposing the face 33 and hands 34 of the movement. The opening 32 is provided with the usual crystal 35 secured in place in any desired manner. 110 The cap 10 with the watch case arranged therewith and forming a part thereof, may

then be used in the usual manner upon a fountain pen body illustrated at 36 in the drawings.

What is claimed is:

5. 1. A watch case comprising a pair of mating semi-tubular sections provided respectively with reduced solid opposite ends, and means engaging said opposite ends for locking the sections against separation.
10. 2. A watch case comprising a pair of mating semi-tubular sections provided respectively with reduced solid opposite ends, and means threadedly engaging said opposite ends for locking the sections against separation.
15. 3. A watch case including a pair of substantially semi-cylindrical mating casing sections, one of which is provided on its flat inner face with a transverse recess and the other of which is provided with longitudinally extending transversely spaced parallel flanges on its inner flat face, adapted, when the casing sections are mated, to fit within the recess for defining a watch movement receiving
20. 25. space.
4. A watch case including a pair of substantially semi-cylindrical mating casing sections, one of which is provided on its flat in-

ner face with a transverse recess and the other of which is provided with longitudinally extending transversely spaced parallel flanges on its inner flat face, adapted, when the casing sections are mated, to fit within the recess for defining a watch movement receiving space, the latter section having an opening extending transversely therethrough and communicating with the watch movement receiving space to expose the face of the movement.

5. A watch case including a pair of substantially semi-cylindrical mating casing sections, one of which is provided on its flat inner face with a transverse recess and the other of which is provided with longitudinally extending transversely spaced parallel flanges on its inner flat face, adapted, when the casing sections are mated, to fit within the recess for defining a watch movement receiving space, said sections having reduced mating opposite extremities and means engaged thereover for detachably holding the sections in mated relation.

Signed at New York, in the county of New York, and State of New York this 7th day of July A. D. 1927.

WILLIAM WISHINSKY.
